UNITED STATES PATENT OFFICE.

JOSEPHI LOCKE, OF TOLEDO, OHIO, ASSIGNOR TO THE W. L. LIBBEY & SON COMPANY, OF SAME PLACE.

DESIGN FOR A PLAQUE.

SPECIFICATION forming part of Design No. 19,116, dated May 28, 1889.

Application filed April 15, 1889. Serial No. 307,343. Term of patent 7 years.

To all whom it may concern:

Be it known that I, JOSEPH LOCKE, a citizen of the United States, and a resident of Toledo, in the county of Lucas and State of Ohio, have 5 invented a certain new and original Design for a Plaque; and I do hereby declare that the following is a full, clear, and exact description of the invention, which will enable others skilled in the art to which it appertains to make and 10 use the same, reference being had to the accompanying drawings, and to the letters of reference marked thereon, which form part of this specification.

My invention relates to a new and original 15 design for a plaque, and the design pertains to the ornamentation of the rim thereof.

The leading feature of my design is the form and shape of the outer surface or rim of a plaque with a fluting or corrugation, and I 20 propose to embody this feature in plaques having an elliptical, hemispherical, oblong, or irregular surface of any desired form in cross-section.

The drawings represent, in Figure 1, a plan 25 view of a circumferential plaque containing the design, and in Fig. 2 a cross-section of the same on lines $x x$, Fig. 1.

In forming a plaque in accordance with my design the outer portion of the edge surface of the same is formed with a fluting or corrugation extending around the circuit of the edge. 30

A designates the plaque of concavo-convex form; B, the edge portion, formed with a series of semicircular flutings or corrugations, 35 C, extending around the edge surface of the same, the edge ornamentation being of a width concentrically to harmonize with the shape and size of the plaque, to give a pleasing symmetry to the same and add to the ornamental appearance thereof. 40

What I claim is—

The design for the ornamentation of a plaque of concavo-convex form herein described and shown, the same consisting of a 45 fluted or corrugated edge or rim surface, surrounding the body portion of the plaque.

In testimony that I claim the foregoing as my own I hereby affix my signature in presence of two witnesses.

JOSEPH LOCKE.
